US0D1039456S

(12) **United States Design Patent** (10) **Patent No.:** **US D1,039,456 S**
(45) **Date of Patent:** **** Aug. 20, 2024**

(54) **FAIRING**

(71) Applicant: **Indian Motorcycle International, LLC**, Medina, MN (US)

(72) Inventors: **Richard J. Christoph**, Minnetrista, MN (US); **William H. Doornink**, Star Prairie, WI (US); **Michael M. Song**, Maple Grove, MN (US); **Michael J. Hanten**, Delano, MN (US); **Ola Ingvar Stenegard**, Stanga (SE)

(73) Assignee: **Indian Motorcycle International, LLC**, Medina, MN (US)

(**) Term: **15 Years**

(21) Appl. No.: **29/828,839**

(22) Filed: **Mar. 1, 2022**

(51) LOC (14) Cl. **12-11**

(52) U.S. Cl. **USPC D12/182**

(58) **Field of Classification Search**

USPC D12/109, 110, 114, 126, 182, 186;
D21/432

CPC ... B62J 17/00; B62J 9/12; B62J 17/10; B62K
19/48

(57) **CLAIM**

We claim the ornamental designs for the fairing, as shown and described.

DESCRIPTION

FIG. 1 is a right front perspective view showing the new design for a fairing for a vehicle;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the fairing shown in broken lines form no part of the claimed design.

1 Claim, 6 Drawing Sheets
